Filed Apr. 2, 1970, Ser. No. 22,215

Term of patent 14 years

Int. Cl. D6—04

U.S. Cl. D33—3

FIG. 1 is a perspective view of a paper bag holder embodying my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an elevational view taken from one side thereof; and

FIG. 7 is an elevational view taken from the side opposite the side shown in FIG. 6.

The fragmentary broken line representation of paper bags in FIG. 1 is for purposes of illustration only.

I claim:

The ornamental design for a paper bag holder, substantially as shown and described.
